T. B. SEARLE

CAN COVER LOCK

Filed Nov. 29, 1922

Inventor
Thomas B. Dearle.

By Harry D. Wallace
Attorney

UNITED STATES PATENT OFFICE.

THOMAS B. SEARLE, OF SYRACUSE, NEW YORK.

CAN-COVER LOCK.

Application filed November 29, 1922. Serial No. 604,004.

To all whom it may concern:

Be it known that I, THOMAS B. SEARLE, a citizen of the United States, residing at Syracuse, in the county of Onondaga and 5 State of New York, have invented certain new and useful Improvements in Can-Cover Locks, of which the following is a specification.

This invention relates to improvements in 10 garbage pails and like receptacles and to the covers therefor, and has for its object to provide novel, simple and effective means for locking the covers of various receptacles in the closed position, for preventing dogs 15 and other animals from removing the covers and gaining access to the contents of the receptacles; the said locking means being effective for preventing the wind and ordinary handling from displacing the 20 covers.

I attain these objects by the means set forth in the detailed description which follows, and as illustrated by the accompanying drawing, in which—

25 Figure 1 is a top-plan view of a garbage can to which one form of my locking mechanism is applied. Fig. 2 is a similar view of a receptacle to which a slightly modified locking mechanism is applied. Fig. 3 is a 30 side elevation and partial central vertical section, the latter being taken on line 3—3 of Fig. 1. Fig. 4 is a similar view, wherein the section is taken on line 4—4 of Fig. 2. Fig. 5 is a top-plan view of the locking mechanism shown in Figs. 1 and 3. And Fig. 6 35 is a similar view of the locking mechanism shown in Figs. 2 and 4.

In the drawing, 2 represents the cylindrical body of the receptacle, having a closed 40 bottom 2', and a normally open top 2^a, which is preferably surrounded by the usual rolled bead 2^b for strengthening the top. Below the bead 2^b the body 2 is operated upon either by spinning or by suitable dies for 45 providing a continuous inwardly facing groove 2^c, which is disposed in a plane parallel to the top 2^a. 3 represents the cover, which is circular and hollow, and preferably consists of a convex top 3', and a continuous drooping flange 3^a, the said flange being of such diameter as to loosely overlap or telescope the top 2^a of the can 2, and when properly adjusted, the under face of the top 3' rests upon the bead 2^b, thereby 55 substantially sealing the mouth 2^a. For ordinary purposes, the cover is held in place by gravity, supplemented by the overlapping of the flange 3^a.

My cover locking mechanism consists of a manually rotatable member 4, which is 60 supported by a shaft 5, upon which the said member may rotate as an axis. 6 represents a substantially U-shaped guard, which is disposed diametrically within the cover 3, the opposite ends of said guard being rigidly 65 secured to the top 3' of the cover by rivets or bolts 6'. In Figs. 3 and 5, the guard 6 is provided with a lug 6^a, which is perforated to receive the shaft 5. 7 and 7' represent similar locking rods or bars whose 70 inner ends are pivoted to the disc 4 by rivets or bolts 7^a. These locking rods then extend radially, in opposite directions, and pass loosely through guiding perforations 6^b in the vertical arms of the guard. Beyond 75 the guard 6, the rods 7 and 7' bend downwardly and then outwardly and their free ends are disposed in the plane of the groove 2^c, which they engage for locking the cover in closed position. The full lines in Fig. 3 80 show the free ends of the locking rods engaging the groove 2^c, while the dotted lines show the said rods withdrawn from the said groove, for releasing the cover. The member 4, as well as the rods 7—7' are manually 85 operable by means of a handle 8, which may be an integral part of the disc 4. The handle 8 is preferably disposed outside of the cover, while the member 4 is preferably disposed entirely within the cover. For this 90 purpose the top 3' of the cover is slotted, as at 3^b. The inner ends of the rods 7—7' are preferably connected to the disc 4 at points that are eccentric to the axis 5, as best seen in Fig. 3, so that a slight rotary movement 95 of the disc, by the raising and lowering of the handle 8 (see full and dotted lines in Fig. 3) effects the reciprocation of the rods 7—7', for unlocking and locking of the cover 3. To remove the cover, the operator grasps 100 the handle 8 and lifts the same upwardly until it is stopped by the bent portions 7^b of the rods engaging the ends 6^c of the guards. In practice, the weight of the cover is such that the handle 8 will yield upwardly 105 sufficiently to withdraw the rods 7—7' from the groove 2^c before the cover starts upwardly. When the cover is replaced on the can, the operator should depress the handle 8, until its free end comes to a stop against 110 the top 3', as shown by full lines in Fig. 3. This downward movement of the handle

forces the free ends of the rods 7-7' into the groove 2^c, and locks the cover in the closed position.

In Figs. 2, 4 and 6, the modification consists chiefly of disposing the disc 4^a horizontally upon the medial portion of the guard 6^a, and in providing a shaft 5' whose lower end passes through the disc and the guard, while its upper end plays in a perforation 3^a of the top 3'. A washer or shoulder 5^a is employed for sealing the opening in the cover, and also prevents the endwise movement of the shaft. Outside of the cover, the shaft 5' is formed into a relatively large hand-loop 5^b, by which the disc 4^a may be rotated, as shown in Fig. 2, for withdrawing the rods 7-7' from the groove 2^c, as explained. The handles 5^b and 8 take the place of the usual permanent handles commonly employed for removing and applying covers of the class. In the modified structure, the can, the cover, the guard, the disc and the locking rods are substantially the same in structure and function, as the corresponding parts shown in Figs. 1, 3 and 5. The locking rods in both structures are attached to the discs at points that are eccentric to the axes of the discs. In this modified device when the cover is replaced, the handle 5^b should be rotated in the opposite direction, for returning the free ends of the rods 7-7' to the groove 2^c, for effecting the locking of the cover.

My cover locking mechanism is extremely simple, and is effective for holding the cover in the closed position without the use of

springs or other auxiliary retaining parts, such as heretofore employed in devices of the class. In both forms of the device, more or less force must be applied to the handles 40 8 and 5^b, in order to disengage the free ends of the rods 7-7'.

Having thus described my invention, what I claim, is—

1. The combination with a can having an annular bead pressed outwardly to form an inwardly facing groove near its open end, and a cover for closing said open end and having a depending flange encircling the bead of the can, of a locking device comprising a rotatable disc supported in the hollow side of the cover, a pair of oppositely facing locking rods pivoted to the disc at points eccentric to the axis of the disc, the free ends of the rods adapted to engage said annular grooves at the opposite sides of the can for locking the cover to the can. 45

2. A can, a cover therefor having a slot, a locking device for the cover comprising a member pivoted on the inner side of the cover having a rigid, curved handle extending out through the slot of the cover, a locking means operable by said member, said handle normally overlying the cover 60 when the latter is locked and adapted to be swung upwardly when removing the cover for simultaneously unlocking the latter. 65

In testimony whereof I affix my signature.

THOMAS B. SEARLE.
